UNITED STATES PATENT OFFICE.

L. D. SPRATT, OF CHICAGO, ILLINOIS, ASSIGNOR OF ONE-HALF TO CHARLES SCHLOTFELDT, OF CHICAGO, ILLINOIS.

RAILROAD TIE.

Application filed January 8, 1923. Serial No. 611,337.

To all whom it may concern:

Be it known that I, L. D. SPRATT, a citizen of the United States, residing at Chicago, in the county of Cook and State of Illinois, have invented certain new and useful Improvements in Railroad Ties, of which the following is a description.

My invention relates to improvements in railroad ties, and more particularly to metallic ties adapted to be substituted for the usual wooden ties.

One of the objects of my invention is to provide means cooperating with my metallic tie for resiliently supporting the load to permit the vertical movement of the rails.

Another object of my invention is to provide a metallic tie of extremely light construction and which shall be extremely strong and durable to serve the purpose for which it is intended.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is a top plan view of a pair of rails supported by my improved tie;

Fig. 2 is a side elevation of the same showing the rails in section;

Fig. 3 is an enlarged section taken substantially on line 3—3 of Fig. 2;

Fig. 4 is a top plan view of a portion of the tie with the rail and cover removed;

Fig. 5 is an enlarged sectional view taken substantially on line 5—5 of Fig. 1;

Fig. 6 is an enlarged sectional view taken substantially on line 6—6 of Fig. 2;

Fig. 7 is a sectional detail showing the manner of securing the cover to the tie; and

Fig. 8 is a detail of a sleeve used in connection with the securing means shown in Fig. 7.

In the drawings, wherein I have illustrated the preferred embodiment of my invention, there is shown a pair of rails 1 of any suitable size or shape and having a flanged base 2. The ties each comprise a pair of hollow box structures 3 preferably

of elongated shape, open at their tops, and spaced apart at opposite ends of a pair of side plates 4, each of said side plates connected at one end to the vertical sides or walls of one of said boxes and at its other end to the other of said boxes, said plates 4 having their upper edge preferably lower than the top edge of the boxes, for a purpose to be more clearly hereinafter described. It will be noted that the opening between the opposed side plates 4 is entirely unobstructed therethrough from top to bottom and from end to end, so that there is no likelihood of water collecting therebetween to rust the material of the plates, this construction also serving to impart a certain degree of flexibility of resiliency to the tie. The material used in making the tie may be such as is desired and preferably metallic.

A cover 5 is adapted to close the open top side of each box structure 3, said cover having its edges flanged at right angles thereto as at 6, so as to slidably engage the vertical walls to the box 3 and prevent any liquids from working their way in between the cover and box. By making the top edges of the side plates 4 lower than the top edges of the boxes, the flanges 6 of the covers need not be notched to accommodate said plates. Carried by the box and projecting into the interior thereof are one or more pins 7 adapted to receive coil springs 8 thereon and form guides therefor. The free end of each of said pins is provided with an axial recess 9 therein to receive the free end of a cooperating guide pin 10, as will be herein-after described.

Each of the pins 8 is arranged immediately below the points where the rails 1 are to be attached to the cover so that they may resiliently support the load on the rails. One or more lead springs 11, carrying pins 10 intermediate their ends, are adapted to be arranged in each of the boxes, said pins slidably engageable in the recesses 9 of the pins 7, said leaf springs supplementing the action of the springs 8 in supporting the load and bearing on the bottom wall of the box and against the cover plate. A single wide leaf spring has been shown but it is to be understood that two or more narrower leaf springs may be substituted therefor.

Said cover and box are provided with registering bolt holes therein to receive bolts 12 spaced at suitable intervals on the

tie. The bolts are preferably flanged as shown and sleeves 13, in the form of resilient lock washers are adapted to encircle the shanks thereof to abut the box 3 and the head of the bolt so that all of the bolts when tightened will adjustably space the cover and box apart a little distance. The sleeve 13 also tends to prevent the accidental rotation of the bolt in the hole because the split ends of said sleeve will bite into the material of the box and bolt to normally hold said parts against relative rotation. A gasket may be interposed between the cover and the head of the bolt, to prevent injury to the parts, avoid constant jars, reduce noise etc.

It is obvious that when the load passes over the tie, the coil and leaf springs will permit the downward movement of the covers relative to the box and that as soon as the load has moved beyond the tie the springs will lift the covers to their normal position.

Clips 13' are used to hold the rail in place on the tie, said clips each having an elongated slot or aperture 14 therethrough to slidably receive a bolt 15 insertible into a threaded aperture in the tie. In order to prevent the rails from spreading, a rib 16 may be provided on the covers at each of the rail-receiving points, said ribs being parallel and adapted to bear against the outer side of the rail flanges. The driving wheel flanges of the train will engage with and prevent the rails from moving inwardly toward one another. It is to be noted that the spacing between the rails is constant at all times, irrespective of whether the tie is flexed or not, so that the rails always act together.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A rail tie comprising a pair of side plates spaced apart throughout and open at the top and bottom, receptacles at the ends

of said plates, covers for said receptacles, means for securing a rail to each of said covers, and means for yieldably maintaining said covers against seating on said receptacles.

2. A rail tie comprising a pair of boxes open at their tops, side plates spaced apart and connected at each end to one of said boxes, a cover for each of said boxes, said covers being independent of each other, means for securing a rail on each of said covers, and means for yieldably maintaining said covers against seating on the box.

3. A rail tie comprising a pair of boxes open at their tops, parallel side plates integral respectively with each side of said boxes and connected at each end thereto, said plates spaced apart throughout, a cover slidably engageable with the vertical walls of each of said boxes, means for yieldably maintaining said covers against seating on said boxes, and means for securing said boxes and covers together.

4. A rail tie comprising a pair of boxes open at their tops and having bounding side walls and bottom walls, a pair of plates secured at each end to said side walls and spaced apart throughout so as to have an opening therethrough from end to end, a cover for each of said boxes, means for detachably securing said covers in place normally above the tops of the boxes, and resilient means for yieldably preventing downward movement of said covers.

5. A rail tie comprising a pair of boxes open at their tops and having bounding sides and bottoms, a pair of plates secured at each end to said side walls below the top edges thereof and spaced apart throughout their length, a cover for each of said boxes having a flange slidably engageable with the vertical walls thereof, means for detachably securing said covers in place normally above the top edges of said boxes and resilient means for yieldably preventing downward seating movement of said covers.

In testimony whereof, I have hereunto signed my name in the presence of two subscribing witnesses.
